UNITED STATES PATENT OFFICE.

JOZEF CHMIELEWSKI, OF HAMTRAMCK, MICHIGAN, ASSIGNOR OF ONE-FOURTH TO
JAN RATKOSKI, OF HAMTRAMCK, MICHIGAN.

SOLDIER'S CHAIR.

1,265,882.

Specification of Letters Patent. Patented May 14, 1918.

Application filed August 13, 1917. Serial No. 185,910.

To all whom it may concern:

Be it known that I, JOZEF CHMIELEWSKI, a citizen of Russia, residing at Hamtramck, in the county of Wayne and State of Michigan, have invented certain new and useful Improvements in Soldiers' Chairs, of which the following is a specification.

The primary object of the present invention is a chair adapted for use by soldiers when taking observations, the structure also being convertible into a serviceable bed or cot.

A further object of the device is the provision of a combined form of a soldier's seat and a convertible extension bed, whereby a bed and a chair are provided in a unitary device readily arranged for use as a chair or as a bed wherever desired.

A still further object of the invention is to provide an elevated resilient seat having a back-rest and convertible into a foldable spring bed structure, the device possessing great strength and durability.

In the drawings forming a part of this application, and in which like reference characters refer to corresponding parts throughout the several views,

Figure 1 is a side elevation of the device set up as a chair,

Fig. 2 is a front view thereof,

Fig. 3 is a side view of the structure arranged as a bed partially extended and a portion of the seat broken away,

Fig. 4 is an enlarged detail perspective view of a side portion of the device showing the latch structure,

Fig. 5 is a top plan view of a portion of the same, and

Fig. 6 is a sectional view taken upon line VI—VI of Fig. 5.

Referring more in detail to the drawings, the device is illustrated in its preferred embodiment, having parallel side rails 10 formed of telescoping sections, the sections 11 being of the greatest diameter arranged at one end of the device and having a foot or base 12 secured thereto while the sections 13 being of the smallest diameter are provided with a cushion 14 at the opposite end of the device.

Intermediate rail sections 15 and 16 are provided with the sections 16 telescoping within the sections 15 while the sections 13 telescope within the sections 15 and the sections 15 telescope within the sections 11 as

best illustrated in Fig. 2 of the drawings. The sections 11, 15 and 16 are arranged with spring catches 17 adjacent their receiving ends, the said catches having spring portions 18 and straight portions 19, the latter 60 adapted for seating within transverse grooves such as 20 arranged in the outer sides of the sections 15, 16 and 13 and adapted for the reception of the spring portions 19 when the sections are in their folded 65 or unfolded relations.

When the device is set up as a chair, the sections 11 and 15 are extended with the latch connections 17 therebetween in their locked positions while the other sections 15, 70 16 and 13 are in their closed arrangements. A spring seat 21 is hinged as at 22 to a cross bar 23 carried by the sections 15 and is provided with a hinged brace 24 centrally connecting the bottom of the seat 21 with 75 a cross bar 25 of the sections 11. A hinged strut 26 in the form of a frame is hinged as at 27 to a cross piece 28 at the free end of the cushion 14 whereby as will be apparent from Figs. 1 and 2 of the drawings, the device 80 may be readily set up as a chair with the side rails 10 in their vertical positions upon the base 12 and with the strut 26 inclined rearwardly thereof preventing the chair from tipping rearwardly. At such 85 times, the brace 24 will be extended and the seat 21 horizontally arranged, with the sections 11 and 15 projected and locked in position by the latches 17.

When it is desired to employ the device 90 as a bed or cot, the brace 24 is folded inwardly bringing the seat 21 adjacent the side rails 10 while the sections 15 are slid within the sections 11. The sections 13 are then moved outwardly of the sections 16 95 while the sections 16 are moved outwardly of the sections 15 thereby extending the canvas or flexible bed bottom 28' which is attached between the inner end of the cushion 14 and a cross bar 29 carried by the sections 100 15 adjacent the hinge bar 23 thereof. A curved supporting bar 30 may be arranged between the sections 16 if desired outwardly of the canvas 28' for assisting in supporting the canvas as well as for bracing the sections 105 16. The side rails 10 being positioned horizontally, the base 12 becomes the foot of the bed while the strut 26 is moved upon its hinge 31 for employing the shorter section 32 thereof as a support for the head portion 110

of the bed, this portion being provided with the cushion 14.

A serviceable device that is foldable into compact form when not desired for use is arranged which may be readily set up as a chair for employing the seat 21, at which times the cushion 14 constitutes the back of the seat; the structure may be readily converted into a bed the canvas 28' constituting the mattress, and the cushion 14 serving as a head rest or pillow. The device may be used in a slightly different manner if desired by using the device as a seat with the sections 13 and 16 projected and dispensing with the use of the strut 26.

What I claim as new is:—

1. A combined chair and bed comprising telescoping side rails having a supporting base at one end and a cushion at its opposite end, an adjustable support for the device at the cushion end thereof, and a combined foot for the bed and seat member hingedly arranged intermediate the said cushion and base.
2. A combined chair and bed comprising telescoping side rails having a supporting base at one end and a cushion at the opposite end, an adjustable support for the device at the cushion end thereof, a combined foot for the bed and seat member hingedly arranged intermediate the said cushion and base, the telescoping sections of the side rails being of different diameters, locking latches between the said sections adapted for retaining the same in their adjusted positions, and a flexible bed bottom connected between the inner end of the cushion and the rail sections upon which the said seat is hinged.
3. A device of the class described comprising a chair-bed having a supporting base, rail sections secured to the said base, a spanning bar for the said sections, an intermediate

pair of rail sections telescoping within the said base sections thereof, a supporting seat hinged to the said intermediate sections, a supporting brace hinged between the said seat and said bar, telescoping end rail sections carried by said intermediate sections, a cushion arranged at the free end of said end sections, and an adjustable supporting strut hinged to the free end of the said cushion.

4. A device of the class described comprising a chair-bed having a supporting base, rail sections secured to the said base, a spanning bar for the said sections, an intermediate pair of rail sections telescoping within the said base sections thereof, a supporting seat hinged to the said intermediate sections, a supporting brace hinged between the said seat and said bar, end rail sections telescoping with each other and with the said intermediate sections, a cushion secured at the free end of said end sections, a flexible bed bottom connected between the said cushion and said intermediate sections, locking means between the said sections when either extended or retracted, and an adjustable hinged strut arranged adjacent the outer end of the cushion.

5. A chair-bed comprising a combined foot-board for the bed and a supporting base for the chair, telescoping rail sections carried thereby, a cushion at the opposite ends of said rail sections from the said base adapted as a pillow for the bed and a back rest for the chair, a hinged supporting member for either the bed or chair hinged adjacent the said cushion, a chair seat, and a bed bottom hinged at their inner sides to adjacent points upon the same sections of rails and operatively supported by the rails.

In testimony whereof I affix my signature.
JOZEF CHMIELEWSKI.
